MECHANICAL CLOTHES WASHER

Peter Eduard Geldhof, Syracuse, N. Y., assignor
to Easy Washing Machine Corporation, Syracuse, N. Y., a corporation of Delaware

Application May 25, 1933, Serial No. 672,824

12 Claims. (Cl. 68—15)

This invention relates to certain new and useful improvements in mechanical clothes washers and pertains more particularly to agitators or dollies and to the mechanism for operating the same.

The general object of the invention is to provide an economically constructed power-driven machine which is capable of expeditiously and thoroughly washing clothes.

10 A more specific object of the invention is to provide an apparatus which will simultaneously produce movement of the clothes and washing fluid in many different directions so as to thoroughly agitate and circulate the clothes and fluid and, at the same time, tend to prevent the clothes from being grouped together.

20 A further object of the invention resides in providing a washing machine having an agitator or dolly which, during its rotary movement about an axis eccentric with respect to the vat, acts upon the clothes from a position at one side of the center of the vat instead of at the center thereof and which also revolves bodily through the clothes and washing fluid in a predetermined path or orbit about the center of the vat during its simultaneous rotary movement whereby the clothes and washing fluid will be revolved about the center of the vat and at the same time be caused to move about the axis of the dolly.

30 Other objects and advantages relate to the mechanism for operating the dolly and transmitting to the dolly its simultaneous rotary and revolving movements, all as will hereinafter more fully appear from the following description taken 35 in connection with the accompanying drawings in which:—

Figure 1 is a vertical sectional view through the center of the washing machine vat and dolly taken in the plane of the line 1—1, Figure 2.
40 Figure 2 is a horizontal sectional view taken on line 2—2, Figure 1.

Figure 3 is an enlarged detail horizontal sectional view taken substantially in the plane of the line 3—3, Figure 1.

45 Figure 4 is an enlarged detail vertical sectional view taken on line 4—4, Figure 3.

Figure 5 is an enlarged detail horizontal sectional view partially in elevation, taken in the plane of the line 5—5, Figure 1.

50 Figure 6 is a vertical sectional view similar to that shown in Figure 1, illustrating a modified form of dolly in connection with my novel drive mechanism.

55 Figure 7 is a horizontal sectional view taken on

line 7—7, Figure 6, illustrating the dolly in plan view.

The invention, as illustrated in Figures 1 to 5 inclusive, of the drawings, comprises a tub or vat 1, preferably circular in horizontal cross-section 5 and which is mounted upon a base 2 which, in turn, is supported by a plurality of legs 3. The vat 1 may be, as shown, provided with a removable cover 4 and has the bottom thereof provided with an opening at substantially its central portion in alignment with a similar opening provided in the upper end 5 of the base 2 for the reception of a flanged bearing sleeve 6. This sleeve 6 has one end externally threaded and extended downwardly through said opening in the vat 15 and base and is screw-threaded in an upwardly extending portion 7 secured to or made integral with a gear case 8 which, in this instance, is shown as being integral with the case of a motor 9. The extension 7 is utilized to secure the sleeve 20 in position by clamping the vat and base between the sleeve flange as 6' and the upper end of the extension 7.

Suitable packing members as 10 may, as shown, be conveniently positioned relative to the sleeve, vat and base so as to render said connection water-tight. The exterior of the upper end of the sleeve 6 is reduced in diameter and has mounted thereon a spur gear 12 which is maintained against movement relative to the sleeve by a key 13 so that the gear will be maintained in fixed 30 predetermined relation to the bottom 14 of the vat 1.

The sleeve 6 is provided with a central opening which extends vertically therethrough concentric with the gear 12. A vertically disposed drive shaft 15 is journaled at one end in the opening in said sleeve and extends downwardly through the extension 7 into the gear case 8, the lower end of said shaft being journaled in the lower end 40 of the extension 7. The shaft is maintained against downwardly axial movement by a collar 16 mounted on said shaft and positioned within the extension 7 above the lower bearing member as 18.

45 The shaft 15 is driven, in this instance, by the motor 9 which may be secured in any well-known manner to the base 2 through the medium of a train of gears which consists, in this instance, of a worm 20 secured to or made integral with the armature shaft 21 of the motor 9 and a worm gear 22 mounted in the gear case 8 and secured to the lower end of the shaft 15. The upper end of the shaft 15 extends a relatively short distance beyond the upper end of the sleeve 6 and has se- 50

cured thereto an arm 24 which extends outwardly from the shaft in a horizontal plane and has secured in the outer end thereof a vertically disposed bearing sleeve 25 which, in turn, has journaled therein a dolly shaft 26. This shaft extends downwardly a short distance below the arm 24 and has secured thereto or made integral therewith a spur gear 27 which, as illustrated more particularly in Figure 3, is in meshing engagement with an idle gear 28.

The gear 28 is rotatably mounted upon a stud 29 which is secured at its upper end to the arm 24, said gear being also in meshing engagement with the fixed gear 12. An inverted cup-shaped cover 23 is secured to the upper face of the arm 24 and has the side walls thereof extended downwardly about the gear members 12, 27 and 28 and terminates a short distance above the bottom 14 of the vat 1, said cover being adapted to encase said arm and gears, with the lower edge thereof terminating so as to substantially completely conceal these members and prevent clothes or fabric being drawn by suction or otherwise into the gears.

The dolly 30 proper is of novel design, being of substantially mushroom or inverted cup-shaped formation, and comprises a substantially flat or slightly curved circular upper end 31 integrally connected at its periphery with a conical side wall 32. This wall extends to within a relatively short distance of the bottom 14 of the vat 1 and is tapered downwardly and outwardly from the end 31 and terminates at its lower edge in an outwardly extending annular flange portion 33 which is slightly inclined downwardly from the inner edge thereof. It is preferable that the outer edge of the flange 33 be irregular in outline to more efficaciously engage the clothing and produce a rubbing cleansing action thereon, and for this purpose, the outer edge of the flange, as shown more clearly in Figure 2, is scalloped or corrugated as at 34.

The dolly is also provided with a plurality of, in this instance seven, radially disposed ribs 35 which extend axially of the side wall 32 from the head 31 to the flange 33, said ribs, in this instance, being of slightly less radial width than the flange 33 and each has the lower end thereof merging into said flange. The dolly head 31 is provided with a pendent socket member 36 which receives the upper end of the dolly shaft 26, said dolly being removably secured to the shaft by a screw 37 screw-threaded into the upper end of the shaft 26.

It will now be observed that when the drive shaft 15 is rotated, the dolly 30 will be carried in a circular path or orbit by the arm 24 about the shaft 15 so that the dolly will be caused to revolve bodily in an orbit about the center of the tub as an axis, while the gears 12, 27 and 28 constitute an epicyclic train which causes the dolly to rotate upon its own axis as it revolves about the vat so that any point upon the surface of the dolly taken in spaced relation to the axis thereof, will describe an epicycloid, and that the number of such curves produced during each complete revolution of the dolly about the shaft 15 will, of course, depend upon the relative sizes of the gears.

It will thus be seen that when the drive shaft 15 is continuously rotated in one direction, the relation of the rotary speed of the dolly about its own axis relative to the revolving speed thereof about the tub depends, of course, upon the relative sizes of the gears constituting the epicyclic

train, while the direction of travel of the dolly during its rotary movement, depends upon the number of gears constituting this train. For instance, if the idle gear 28 is omitted and the gear 27 mounted upon the dolly shaft caused to mesh directly with the fixed gear 12, the direction of the rotary movement of the dolly about its own axis will be the reverse of that when said dolly is driven through the medium of the idle gear as 28. In other words, this dolly drive mechanism consisting of the arm 24 and gears 12, 27 and 28 constitute a planetary gear mechanism which not only rotates the dolly about its own axis, but revolves the dolly about the center of the tub as an axis which action of the dolly produces a progressive whirling or swirling movement of the washing fluid and the clothes contained therein about the interior of the tub. This action of the dolly not only causes the clothes and washing fluid to be vigorously agitated but also produces a continuous movement of the clothes over the dolly surface with the result that in a reasonably short time, all of the clothes have come into frictional contact with the upper surface of the dolly under a yielding pressure produced by the swirling water and will thereby thoroughly and efficaciously wash the clothes in a reasonably short period of time and with a minimum amount of wear upon the clothes.

In Figures 6 and 7, I have illustrated a modified form of dolly applied to my novel drive mechanism. The dolly shown herein extends from close proximity to the bottom 14 of the vat to a position above the normal level of the washing fluid near the upper end of the vat.

In this instance, the bearing sleeve as 40 mounted in the outer end of the arm 24 is extended some distance above the arm so as to terminate near the upper end of the dolly, while the dolly shaft as 41 extends upwardly through the sleeve 40 to a point above said sleeve. The interior of the sleeve 40 is, as shown, preferably of greater diameter than the outside diameter of the shaft 41 and is provided with a bearing bushing 42 composed of brass or other suitable material at the upper and lower end thereof for rotatably supporting the shaft 41.

The dolly, as 44, in this instance, comprises a conical body portion 45 preferably having opposite sides thereof extending in straight diverging planes from the upper end to the base. The upper end of the body 45 is provided with an interior pendent socket member 46 which normally rests upon the upper end of the sleeve 40 and receives the upper end of the shaft 41. Any suitable means may be employed to secure the shaft to the dolly so that said dolly and shaft will rotate in unison, such as the pin 47.

The dolly may further be supported near its lower end by the sleeve 40, and for this purpose, is formed with a plurality of, in this instance four, inwardly projecting flanges 48 which have the lower ends thereof terminating in slightly spaced relation to the cover 23. Each of the flanges 48 is formed at its lower inner edge with a recess for receiving a bearing bushing 49 which has a press fit in the flanges or may be otherwise permanently secured thereto and is adapted to rotate about the exterior surface of the sleeve 40.

A series of, in this instance three, spirally arranged blades 50 are secured to or made integral with the conical body 45 of the dolly to project outwardly therefrom. These blades are preferably arranged in uniform circumferential spaced

relation about the body and extend downwardly from the top thereof to the bottom. Although these blades may project a uniform distance from the surface of the dolly throughout their length, it is preferable that they should gradually increase in radial width as they extend downwardly from their upper ends to their lower ends.

Further, the spirally arranged blades are preferably inclined with respect to a line normal to the surface of the cone body. This angle of inclination may be uniform throughout the length of the blades, but preferably gradually increases from the upper end of the blade toward the lower end, said lower ends projecting substantial distances radially from the periphery of the dolly at its base. Further, the degree of curvature of the spiral blades may vary substantially, but it is found that good results are obtained when the lower ends of the blades terminate approximately 180° around the circumference of the cone from the termination of the upper ends of the blades. In this manner, channels or passageways are formed between the adjacent blades which extend spirally around the cone surface of the dolly and open at their lower ends to the bottom of the tub beyond the periphery of the base of the dolly. Also, the inclination of the blades with respect to a line normal to the cone surface forms a pocket upon one side of the blade, as indicated at 51, and the side of the blade toward this pocket may, for the purpose of this specification, be termed the rearward side of the blade as it revolves about the axis of the shaft 41 and which causes the water to circulate in the vat 1 about the dolly 44.

In other words, by referring to Figure 3, it will be noted that when the arm 24 is rotated in a counterclockwise direction, the dolly shaft will be rotated about the axis thereof in a clockwise direction so as to produce what may be termed a rotary movement of the dolly as 44 about the axis of the dolly shaft 41 in a rearward direction in respect to the inclination of the blades 50 so that the washing fluid and clothes are caught by the spirally arranged blades and moved or rotated about the axis of the dolly shaft, and as the dolly is revolved about the tub in a counterclockwise direction simultaneously with the rotary movement of the dolly just described, the clothes and washing fluid immediately ahead of the dolly will be engaged by the blades and moved outwardly between the dolly and adjacent outer wall of the vat and then thrown off from the dolly at the rear thereof with a swirling motion which produces a tumbling turbulent mass at the rear of the dolly wherein the clothes are separated or unfolded and prevented from being bunched or grouped. Moreover, the spiral arrangement of the blades in relation to the direction of rotation of the dolly, that is, the extension of the blades from the top of the dolly spirally downwardly and rearwardly over the face of the conical body, further enhances the agitation and cleansing of the clothes in that the clothes as they are engaged by the dolly, are urged downwardly toward the base of the cone body and bottom of the vat and compressed or squeezed to a certain extent between the dolly and adjacent portion of the peripheral wall of the vat as said clothes move between the dolly and wall, with the result that as the clothes are thrown off at the rear of the dolly, they again expand to normal and move upwardly in the washing fluid.

Although I have shown and described specific forms and construction of apparatus as constit-

tuting embodiments of the invention, I do not wish to restrict myself to the details of constructions or forms shown, as various changes and modifications may be readily made, without departing from the spirit of this invention as set forth in the appended claims.

I claim:

1. In a washing machine having a vat, an agitator therein comprising an upright frusto conical body portion, an annular flange integral with the body portion at the lower end thereof, and radially extending blades disposed axially of the body portion from the upper end thereof to said flange means for rotating said agitator about its axis and means for moving said agitator in an orbit within said vat.

2. In a washing machine comprising a vat, an agitator rotatably mounted in the vat, means for moving said agitator in an orbit within the vat, said agitator comprising a cone-shaped body portion and spiral means extending substantially axially of said body portion for circulating the water and clothes.

3. In a washing machine comprising a vat, an agitator rotatably mounted in the vat, means for moving said agitator in an orbit within the vat, said agitator comprising a cone-shaped body portion and a spiral blade extending from the body portion for circulating the water and the clothes.

4. In a washing machine comprising a vat, an agitator rotatably mounted in the vat, means for moving said agitator in an orbit within the vat, said agitator comprising a cone-shaped body portion and a spiral blade extending from the body portion, said blade being inclined from normal to said central portion.

5. In a washing machine comprising a vat, an agitator rotatably mounted in the vat, means for moving said agitator in an orbit within the vat, said agitator comprising a central upstanding body portion and a plurality of spiral blades extending substantially axially of said body portion for circulating the water and the clothes.

6. In a washing machine comprising a vat, an agitator rotatably mounted in the vat, means for moving said agitator in an orbit within the vat, said agitator comprising a central upstanding body portion having a cone-shaped surface and a plurality of spiral blades extending outwardly from said body portion.

7. In a washing machine comprising a vat, an agitator rotatably mounted in the vat, means for moving said agitator in an orbit within the vat, said agitator comprising a central upstanding body portion having a cone-shaped surface and a plurality of spiral blades extending outwardly from said body portion, said blades being inclined to a normal to said surface.

8. In a clothes washing machine, in combination, a vat, a rotatable agitator therefor and a drive mechanism for the agitator comprising a drive shaft passing upwardly through the bottom of the vat, a driven shaft, means for mounting said driven shaft wholly within the vat and eccentrically of the drive shaft for revolving said driven shaft about the axis of said drive shaft, means for positively rotating said driven shaft during the movement of revolution thereof, and means connecting the agitator with the upper end of the driven shaft to be driven thereby, said agitator having a part extending over the top and around the sides of said drive mechanism to form a protecting housing therefor.

9. In a clothes washing machine, in combina-

75

tion a vat, an agitator mounted in the vat at one side of the center thereof, means for moving said agitator in an orbit about the center of the vat, means for rotating said agitator about its axis, said agitator comprising a frusto conical body and a substantially flat radially extending blade disposed axially of the body from the upper end of said body downwardly.

10. In a clothes washing machine, in combination, a vat, an agitator mounted in the vat at one side of the center thereof, means for moving said agitator in an orbit within the vat, means for rotating said agitator about its axis, said agitator comprising an upright frusto conical body, an 15 annular flange integral with the body at the lower end thereof and a radially extending blade disposed axially of the body from the upper end thereof to said flange.

11. In a washing machine, a vat, a drive shaft 20 projecting through the bottom of the vat, an agitator supported by said drive shaft in eccentric relation thereto, said agitator having an interior

at least partially hollow, and means mounted in said hollow interior and connected to the drive shaft and to said agitator for rotating the agitator about the axis of the drive shaft and about the axis of the agitator simultaneously. 5

12. In a washing machine, a vat, a drive shaft projecting upwardly through the bottom of the vat, an agitator supported by said drive shaft in eccentric relation thereto, said agitator having an interior at least partially hollow with the drive 10 shaft projecting upwardly into said hollow interior, driving mechanism for said agitator mounted in said interior and comprising a fixed gear with respect to which said shaft is rotatable, a shaft co-axial with said agitator, a gear rigidly mounted 15 on said second shaft and operatively connected with said first gear for rotating the agitator about its own axis, and a member rigidly secured to the drive shaft and journaled on the second shaft for rotating the agitator about the axis of the 20 drive shaft.

PETER EDUARD GELDHOF.
